UNITED STATES PATENT OFFICE

EDDY FAIRCHILD, OF GLEN RIDGE, NEW JERSEY

DESIGN FOR A BOWL OR SIMILAR ARTICLE

Application filed August 10, 1929. Serial No. 32,371. Term of patent 7 years.

To all whom it may concern:

Be it known that I, EDDY FAIRCHILD, a citizen of the United States, residing at Glen Ridge, in the county of Essex and State of New Jersey, have invented a new, original, and ornamental Design for Bowl or Similar Article, of which the following is a specification, reference being had to the accompanying drawing, forming part thereof.

The figure on the drawing is an elevation view of a bowl, embodying my new design.

In plan, the bowl shown is substantially circular.

I claim:

The ornamental design for a bowl or similar article, as shown and described.

EDDY FAIRCHILD.
